UNITED STATES PATENT OFFICE.

JAMES A. EDEN, JR., OF SPRINGFIELD, MASSACHUSETTS, ASSIGNOR TO WALTER H. FOSTER, OF NEW YORK, N. Y.

BOLT CENTERING, FACING, AND POINTING MACHINE.

Application filed July 7, 1925. Serial No. 41,948.

This invention relates in general to machine tools and while not limited thereto is particularly directed to means for drilling centering holes in the ends of bolt blanks and for facing the underside of the head and pointing or machining the end of the work blank opposite the head.

An embodiment of the invention is illustrated in the accompanying drawings in which—

Fig. 1 is a front elevation of the machine; Fig. 2 is a top plan view thereof;

Fig. 3 is an end elevation of the machine as viewed from the right of Fig. 1;

Fig. 4 is an end elevation of the machine as viewed from the left of Fig. 1;

Fig. 5 is an enlarged plan of the part shown at the left in Fig. 1;

Fig. 6 is an enlarged plan of the part shown at the right of Fig. 1;

Fig. 7 is an enlarged elevation of the center drilling mechanism shown in Fig. 1, an intermediate portion of the machine being broken away;

Fig. 8 is a detail in central longitudinal section of the center drilling mechanism shown at the left in Fig. 7;

Fig. 9 is a transverse section on line 9—9 of Fig. 8;

Fig. 10 is an enlarged vertical longitudinal section on line 10—10 of Fig. 2;

Fig. 11 is a transverse vertical section on line 11—11 of Figs. 2 and 10;

Fig. 12 is a detail view of parts lying to the rear of the plane section illustrated in Fig. 11;

Fig. 13 is a vertical transverse section taken on line 13—13 of Fig. 5 and illustrating part shown to the rear of plane of section of Fig. 12;

Fig. 14 is a transverse sectional view taken on line 14—14 of Figs. 1 and 2;

Fig. 15 is a sectional plan on line 15—15 of Fig. 14;

Fig. 16 is a detail section on line 16—16 of Fig. 15;

Fig. 17 is a transverse vertical section taken on line 17—17 of Figs. 1 and 2;

Fig. 18 is a sectional view illustrating in detail the parts shown in elevation immediately thereunder in Fig. 17;

Fig. 19 is a sectional view on line 19—19 of Fig. 18;

Fig. 20 is a plan view of the dead center shown at the right in Figs. 1 and 2;

Fig. 21 is a longitudinal section on line 21—21 of Fig. 20;

Fig. 22 is a transverse section on line 22—22 of Fig. 20;

Fig. 23 is a view of a rough drop forged bolt blank;

Fig. 24 is a view of the same blank after it has been center drilled;

Fig. 25 illustrates the blank after the bolt head has been faced on the underside, the shank necked adjacent the head, and the end pointed.

Fig. 26 is a front view of an alternative form of chuck;

Fig. 27 is a section on line 27—27 of Fig. 26;

Fig. 28 is a detail section on line 28—28 of Fig. 26;

Fig. 29 is a detail view of an attachment.

Referring in detail to the drawings, the machine includes a base pan 10 supported on suitable legs 12 which are secured to one another by longitudinally extending rods 14 which also form a support for a motor 16 carrying a pulley 18 which is connected by means of a belt 20 with a pulley 22 carried on one end of a main drive shaft 24 which is journalled in suitable bearings 26 and 28 secured to the base pan 10.

The shaft 24 carries a sprocket 30 which is connected by a chain 32 with a sprocket 34 carried on a shaft 36 which is adapted to rotate the centering drill 38 shown at the left in Fig. 1. A similar centering drill 40 shown at the right in Fig. 1 is adapted to be driven by a shaft 42 which carries a sprocket 44 which is connected by means of a chain 46 with a sprocket 48 secured to a short shaft 50. Also carried on this shaft is a gear 52 which meshes with a gear 54 slidably mounted on the main shaft 24 and adapted to be rotated thereby.

The center drill 40 and its operating mechanism is mounted on a tail-stock 56 which slides on suitable guides formed on the base of the machine. This tail-stock is arranged to be adjusted longitudinally of the base by means of feed screws 58 and 60 which pass through suitable nuts carried in the tail-stock. These two screws are arranged to be rotated in unison by a suitable crank handle 64, sprockets 66 and 67 and chain 68. The sprockets 44 and 48 and the gears 52 and 54 are located between bracket members 70 and 72 carried by the tail-stock. Hence, when the latter is adjusted to accommodate dif-

ferent sizes of work the gear 54 will slide along on the shaft 24.

The drills 38 and 40 are mounted in similar holders one of which is illustrated in detail in Fig. 8. As here shown, the drill is carried by a known form of drill chuck 74. This is carried on the end of a shaft 36. The drill is fed forward by means of a holder 76 slidingly mounted in a suitable bearing 78. Said holder is provided on its underside with rack teeth 80 which mesh with a pinion 82 carried on a stub shaft 84. The holder 76 has secured thereto a collar 86 which is adapted to limit the longitudinal movement of the holder and, hence, the inward movement of the drill 38.

Means are provided for simultaneously causing both drills 38 and 40 to approach the opposite ends of the work. The mechanism is such that both drills can be actuated from a point in juxtaposition to either of the drills. As shown in Fig. 9 the stub shaft 84 which carries the pinion 82 has keyed thereto a sleeve 88 having a flange 89 to which is riveted a sprocket 90. Loosely mounted on the sleeve 88 is another sprocket 92. A crank handle 94 is secured to the stub shaft 84. Rotation of the crank will turn the shaft 84 and sprocket 90 and pinion 82. One end of a chain 96 engages the underside of a sprocket 90 and its extremity is pinned or dead ended on the sprocket. The other end of this chain is wrapped over the top of a similar sprocket carried on a stub shaft 98 mounted in suitable bearings in the tail-stock and provided with a suitable pinion (similar to that shown at 82 in Fig. 9) and arranged to feed the drill 40 to and from the work. The chain 96 carries on its end a weight 100. The stub shaft 98 carries a sprocket 102 and a crank handle 104 similar to that provided on the stub shaft 84. A chain 106 is dead ended on the sprocket 102 and passes from the underside thereof around the top of the sprocket 92 on the shaft 84 and carries a weight 108 on its end. By the above described connections, it will be appreciated that by turning either of the crank handles 94 or 104, both of the drills will be caused to move either toward or from the work indicated at W. When the tail-stock is adjusted for different sizes of work, the chains can be lifted to initially position the ends of the drill. And the setting of the stop collar 86 will determine the depth to which the center drills penetrate the work.

The work to be center drilled is held by an improved holding means which engages the work blanks in such a way that the axes thereof are automatically aligned with the center drills. These work holders are arranged to be rapidly and accurately set and released.

The work holder comprises upper and lower jaws 110 and 112 mounted on the fixed

part of the machine and adapted to grip the work near one end, and similar jaws 114 and 116 carried by the movable member or tail-stock and adapted to grip the other end of the work. The construction of both work holders is practically the same and a description of one will suffice for both, it being remembered, however, that one holder travels with the tail-stock and is arranged to be operated in the same manner regardless of its position of adjustment. As shown in Figs. 11 and 13, the upper jaw 110 of the work holder is provided on its underside with teeth 111 adapted to secure a good grip on the work blank W. The lower jaw 112 is provided with similar teeth 113. The jaw 110 is provided at the rear with a downwardly extending shank 118 which slides in a groove 120 formed in the supporting bracket 122. Mounted in a suitable recess in the bracket is a spring 124 which bears on the underside of a stud 126 secured to the back of the shank 118 and tending to normally lift the jaw 110 out of engagement with the work. The lower end of the shank 118 extends forwardly and terminates in an upward projection 128 which is located beneath the center of the jaw 112. Longitudinally aligned cam members 130 and 132 (Fig. 7) are jointed to one another by dowels 134. The cam member 130 is arranged to actuate the jaws 110 and 112 and the similar elongated member 132 is adapted to actuate the jaws 114 and 116 carried by the tail-stock regardless of its position of adjustment. The respective cam members 130 and 132 are secured to cylindrical bearing members such as shown at 135, in Figs. 7 and 13. The members 135 are rotatable in bearings 136. The cam members 130 and 132 are so arranged that a heavy weight tends to hold the jaws firmly gripped against the work. The weight 138 for effecting this gripping action as shown in Figs. 4 and 13 is carried by a chain 140 one end of which is dead ended on a sprocket 142 secured to a shaft 144 the outer end of which is journaled in a suitable bearing 146 and the inner end of which is secured to the cam member 130. As thus arranged, it is clear that when the cam members 130 and 132 are in the position illustrated in Figs. 11 and 13 the weight exerts a force tending to hold the jaws 110 and 112 at one end and 114 and 116 at the other end of the blank firmly in place. For releasing the grip on the jaws, the shaft 144 is provided with a hand lever 148 by which the cam members 130 and 132 can be turned so as to permit the lower jaw to drop and the upper jaw to be raised by the spring 124.

For holding the jaws in open position, I provide a spring pressed latch 150 shown in Fig. 11 which has a tooth 152 for engagement with a similar tooth 154 carried by the handle 148. When the handle is in the dotted position shown in Fig. 11, the latch is adapted to prevent the weight from turning the cam. A

ferent sizes of work the gear 54 will slide along on the shaft 24.

The drills 38 and 40 are mounted in similar holders one of which is illustrated in detail in Fig. 8. As here shown, the drill is carried by a known form of drill chuck 74. This is carried on the end of a shaft 36. The drill is fed forward by means of a holder 76 slidingly mounted in a suitable bearing 78. Said holder is provided on its underside with rack teeth 80 which mesh with a pinion 82 carried on a stub shaft 84. The holder 76 has secured thereto a collar 86 which is adapted to limit the longitudinal movement of the holder and, hence, the inward movement of the drill 38.

Means are provided for simultaneously causing both drills 38 and 40 to approach the opposite ends of the work. The mechanism is such that both drills can be actuated from a point in juxtaposition to either of the drills. As shown in Fig. 9 the stub shaft 84 which carries the pinion 82 has keyed thereto a sleeve 88 having a flange 89 to which is riveted a sprocket 90. Loosely mounted on the sleeve 88 is another sprocket 92. A crank handle 94 is secured to the stub shaft 84. Rotation of the crank will turn the shaft 84 and sprocket 90 and pinion 82. One end of a chain 96 engages the underside of a sprocket 90 and its extremity is pinned or dead ended on the sprocket. The other end of this chain is wrapped over the top of a similar sprocket carried on a stub shaft 98 mounted in suitable bearings in the tail-stock and provided with a suitable pinion (similar to that shown at 82 in Fig. 9) and arranged to feed the drill 40 to and from the work. The chain 96 carries on its end a weight 100. The stub shaft 98 carries a sprocket 102 and a crank handle 104 similar to that provided on the stub shaft 84. A chain 106 is dead ended on the sprocket 102 and passes from the underside thereof around the top of the sprocket 92 on the shaft 84 and carries a weight 108 on its end. By the above described connections, it will be appreciated that by turning either of the crank handles 94 or 104, both of the drills will be caused to move either toward or from the work indicated at W. When the tail-stock is adjusted for different sizes of work, the chains can be lifted to initially position the ends of the drill. And the setting of the stop collar 86 will determine the depth to which the center drills penetrate the work.

The work to be center drilled is held by an improved holding means which engages the work blanks in such a way that the axes thereof are automatically aligned with the center drills. These work holders are arranged to be rapidly and accurately set and released.

The work holder comprises upper and lower jaws 110 and 112 mounted on the fixed

part of the machine and adapted to grip the work near one end, and similar jaws 114 and 116 carried by the movable member or tail-stock and adapted to grip the other end of the work. The construction of both work holders is practically the same and a description of one will suffice for both, it being remembered, however, that one holder travels with the tail-stock and is arranged to be operated in the same manner regardless of its position of adjustment. As shown in Figs. 11 and 13, the upper jaw 110 of the work holder is provided on its underside with teeth 111 adapted to secure a good grip on the work blank W. The lower jaw 112 is provided with similar teeth 113. The jaw 110 is provided at the rear with a downwardly extending shank 118 which slides in a groove 120 formed in the supporting bracket 122. Mounted in a suitable recess in the bracket is a spring 124 which bears on the underside of a stud 126 secured to the back of the shank 118 and tending to normally lift the jaw 110 out of engagement with the work. The lower end of the shank 118 extends forwardly and terminates in an upward projection 128 which is located beneath the center of the jaw 112. Longitudinally aligned cam members 130 and 132 (Fig. 7) are jointed to one another by dowels 134. The cam member 130 is arranged to actuate the jaws 110 and 112 and the similar elongated member 132 is adapted to actuate the jaws 114 and 116 carried by the tail-stock regardless of its position of adjustment. The respective cam members 130 and 132 are secured to cylindrical bearing members such as shown at 135, in Figs. 7 and 13. The members 135 are rotatable in bearings 136. The cam members 130 and 132 are so arranged that a heavy weight tends to hold the jaws firmly gripped against the work. The weight 138 for effecting this gripping action as shown in Figs. 4 and 13 is carried by a chain 140 one end of which is dead ended on a sprocket 142 secured to a shaft 144 the outer end of which is journaled in a suitable bearing 146 and the inner end of which is secured to the cam member 130. As thus arranged, it is clear that when the cam members 130 and 132 are in the position illustrated in Figs. 11 and 13 the weight exerts a force tending to hold the jaws 110 and 112 at one end and 114 and 116 at the other end of the blank firmly in place. For releasing the grip on the jaws, the shaft 144 is provided with a hand lever 148 by which the cam members 130 and 132 can be turned so as to permit the lower jaw to drop and the upper jaw to be raised by the spring 124.

For holding the jaws in open position, I provide a spring pressed latch 150 shown in Fig. 11 which has a tooth 152 for engagement with a similar tooth 154 carried by the handle 148. When the handle is in the dotted position shown in Fig. 11, the latch is adapted to prevent the weight from turning the cam. A

trip 156 is pivoted at 158 to the handle and is so arranged that when the operator grasps the handle at the end, he will release the latch thus permitting the weight to turn the cams 5 and thereby grip the blank at both ends.

After a work blank, such as a rough forged bolt shown in Fig. 23, has been operated upon by the center drills 38 and 40, it will be in condition for further machine work which is 10 preferably done while the work is supported on centers. Therefore, I preferably remove the work from the grip of the holding jaws and insert it between the live and dead centers 160 and 162. To facilitate the rapid insertion and removal of the bolt blanks from 15 between the live and dead centers, I provide improved means for moving the dead center.

The dead center 162 is mounted in a longitudinally movable member 164 (Fig. 21) 20 which is slidable in a bracket 166 secured to the tail-stock 56. The member 164 has a block or projection 168 secured thereto which is adapted to ride in a cam slot 170 formed in a transversely movable slide 172 which is 25 mounted in a suitable groove or recess formed in the upper surface of the bracket 166. A plate 174 is secured to the bracket 166 by suitable screws 176. It will be appreciated that the transverse sliding movement of the 30 grooved plate 172 will cause the dead center 162 to either move in or out according to the direction of movement of the plate. For operating the sliding plate, I provide a handle 178 the forward end 180 of which is reduced in diameter and passes through an opening in a plate 182 secured to the end of the cam plate 172. The end of the handle 180 carries a spring 184 one end of which bears on a collar held in place by a nut 186 40 threaded on the end 180 of the handle. The opposite end of this spring bears against the plate 182. In operating the handle 178 to withdraw the center, the operator pushes on the handle and this act causes the shoulder 45 188 to push against the plate 182 and thus cause the cam to withdraw the member 164 and with it the dead center 162. When a new work piece is inserted the operator pulls the handle until the dead center 162 50 encounters the end of the work. He then pulls the handle a little farther to exert a slight compression on the spring 184 and then engages one of the perforations 188 formed in the handle with a locking pin 190 secured to the plate 174. It is thus seen that the dead center is yieldingly held in engagement with the work W.

The live center 160 is seated in the tapered socket 192 formed in the end of the drive 60 spindle 194 which is rotatably mounted in head stock bearings 196 and 198. At one extremity the spindle 194 is reduced in diameter and screw threaded as at 199 for engagement with a similarly threaded hub of a face plate 200 to the front face of which is screwed

or otherwise secured a chuck ring 202 having a hexagonal aperture 204 formed therein for engagement with the head H of the work piece W.

Loosely mounted on a reduced portion of the spindle 194 is a spur gear 206 having a rearwardly extending hub 208. To the latter is secured a larger gear 210. The main shaft 24 has slidably secured thereon gears 212 and 214 which are arranged to be meshed respectively either with the gear 206 or 210, the first pair being used to rotate the work at high speed and the latter pair being engaged when a slower rotation of the work is desired. The gear 206 is provided with a suitable recess to 70 accommodate a spring pressed clutch dog 216 the end of which is adapted to enter a recess 218 formed in the clutch member 220 keyed to the spindle 194. A sliding block 222 seated in the recess 218 is arranged to prevent the 75 entrance of the pin 216 into the recess 218 when held in the position illustrated in Fig. 10 by the end 224 of a clutch trip lever 226 which is pivotally mounted at 228 to a fixed 80 bracket 230 (Fig. 14). The block 222 is 85 formed with a recess 232 the entrance portion of which is bevelled off at 234. The extremity of the trip lever 226 is similarly bevelled and is adapted to reset the block 222 after the clutch has been tripped. The width 90 of the trip lever 226 is such that it fits freely within an annular groove 235 formed in the clutch member 220. As long as the end 224 of the lever 226 is depressed, it is clear that the block 222 will be held in the position 95 shown in Figs. 10 and 15 thus the gears 206 and 210 rotate idly on the spindle 194. When the end 224 of lever 226 is elevated, however, the spring 217 forces the clutch dog 216 into the recess 218 thus turning the clutch member 220 which is keyed to the spindle. 100

A foot treadle 236 pivoted at 238 to the frame of the machine is connected by a link 240 with a crank arm 242 (Fig. 14) carried by a rock shaft 244 having an arm 246 thereon 110 which is connected by a link 248 at 249 with one end of the above mentioned clutch trip lever 226. Through these connections, it will be seen that when the operator depresses the treadle 236 the clutch dog 216 will be permitted to establish a driving connection between the main drive shaft 24 and the spindle 194. The duration of this driving connection is controlled by a timing disc 250 carried on a shaft 252 which is connected by a gearing (hereinafter referred to) to the spindle 115 194. The timing disc 250 is provided with a notch 254. The extremity of the clutch trip lever 226 is formed with a projection 227 which rides on the periphery of the disc 250 after the clutch has been manually tripped thus holding the free end 224 in such position that the clutch member 220 remains operatively connected with the gear 206. 120 However, as soon as the notch 254 reaches the 130

position shown in Fig. 14, a spring 256 rocks the lever 226 so as to depress its trip end 224, hence, as the clutch member 220 approaches the position shown in Fig. 15 the bevelled end 5 thereof strikes the bevelled portion 234 of the block 222 and thus pushes the clutch dog 216 clear of the clutch member 220.

The gearing connecting the spindle 194 with the shaft 252 previously referred to, includes a pinion 258 which is keyed to the spindle 194 and meshes with a gear 260 carried on a stub shaft 262 mounted in suitable fixed bearings 264. The shaft 262 carries a pinion 266 meshing with a gear 268 secured to a 10 shaft 270 mounted in suitable fixed bearings 272. The shaft 270 has detachably secured thereto a change gear 274 meshing with a change gear 276 carried on the end of the above mentioned shaft 252 which carries the 15 timing disc. The clutch and gearing above described provides driving means whereby cutting tools to be presently described can be brought into play in a predetermined manner so as to machine or finish desired parts of 20 the work. The machine illustrated is provided with tools for facing the underside of the bolt head and for pointing the end of the blank. These tools are moved toward the work by cams carried on the shaft 252. 25 Through the above described gearing these cams make one complete cycle and come to rest at the end thereof. During this cycle, of course, the work makes many revolutions.

When the work blank is inserted between 30 the live and dead centers the underside of the head as indicated at *w* in Fig. 24 is a rough surface. The end of the blank as indicated at *e* is also uneven. The tools are provided for machining the underside of the 35 head smooth as indicated at *W*¹ in Fig. 25 and for "necking" the shank of the bolt adjacent the head as indicated at *W*². Another tool is provided for "pointing" or fac- 40 ing the end to a smooth finish as indicated 45 at *e*¹ in Fig. 25.

For making the roughing cut under the head of the bolt blank, I provide a roughing tool 278 (Fig. 11) carried in a holder 280 secured to a tool slide 282 mounted on a guide 50 284 secured to the base of the machine. Adjustably secured to the slide 282 by bolts 283 is a bracket 286 carrying a roller 288 for coaction with a cam 290 secured to the shaft 252. The adjusting screw 292 engages posts 55 294 and 296 carried respectively by the slide 282 and the bracket 286 so as to permit slight adjustment to compensate for wear on the cutting tool or for setting the parts for operation on blanks of varying sizes. The under- 60 side of the slide 282 is recessed for the reception of a spring 298 one end of which bears on a fixed stud 300 and the other end of which bears on a plate 302 secured to the rear of the slide. As thus arranged, it is clear that 65 upon rotation of the shaft 252 the cam 290

will advance the roughening tool 278 while making the cut and on completion thereof the spring 298 will return the tool to a starting position determined by the contour of the cam. 70

After the roughing cut has been made by the tool 278 a finishing tool 304 comes into play and takes a very light cut on the underside of the bolt head and also "necks" or takes a light cut to form the finished portion 75 indicated at *W*² in Fig. 25. If desired this neck, of course, can be formed initially by the roughing tool 278 and finally finished by the tool 304. The finishing tool is carried in a holder 306 which is adjustably secured to the free end 308 of a lever 310 pivoted on a stud 312 secured to a bearing 314. This lever carries at its outer end a cam roller 316 for coaction with a finishing cam 318 secured to the shaft 252. A spring 320 is anchored at 80 one end to any fixed part of the machine and at the other end to a pin 322 secured to the underside of the lever 310. The relative positions and contours of the cams 290 and 318 can be varied to suit requirements of the 85 work as will be understood.

For "pointing" the blank, that is to say, fac- 90 ing the end as indicated at *e*¹ in Fig. 25, I provide a pointing tool 324 which is curved at 95 326 to the desired contour. This tool is mounted in a holder 328 which is secured to a slide 330 movable on a suitable guide 332 formed on the movable tailstock 56. The slide 330 carries a bracket 334 which is adjustable relatively thereto by means of a 100 screw 337. At its end the bracket 334 carries a roller 336 for coaction with a cam 338 on the shaft 252. The slide 330 is adapted to be advanced toward the work by the cam 338 and a spring 340 is provided for returning 105 the slide under control of the cam.

The advantages of the machine constructed as above described will be readily apparent to those skilled in the art. It will be seen at once that by mounting one of the centering 110 drills and one of the work holding clamps on the movable slide or tail-stock, that the machine can be readily set for work on blanks of different lengths. The flexible crossed chains for transmitting movement from one centering drill spindle to the other is quickly and easily adjusted when the tail-stock is moved to operate on longer or shorter blanks than those shown. The automatic cam actuated cutting tools accomplish their work in response to a foot actuation of the clutch treadle after which the operator is free to clamp another work blank in place and center drill the same while the previously centered blank is being automatically pointed at the end and 115 faced under the head.

In operation, assuming that the clamping jaws 110, 112, 114 and 116 are open and the handle 148 is in the dotted position shown in 120 Fig. 12, the operator inserts a rough forged 125

blank such, for example, as shown in Fig. 23 and then grasps the trip lever 156. This trips the latch 150 and permits the weight 138 to turn the cam members 130 and 132 to the position illustrated in Fig. 13 so that the weight exerts a firm gripping action on the work. The operator now turns either the handle 92 or 104 which through the rack and pinions described will cause the center drills 38 and 40 to approach one another and drill tapered centering holes in the opposite ends of the work to a depth determined by the position of the stop 86. Either the handle 92 or 104 is then operated to retract the center drills 15 and the clamp control handle 148 is depressed to release the work from the holding jaws. The operator then inserts the head H of the blank into the hexagonal aperture 204 of the chuck 202 and pulls the handle 178 so as to move the dead center 162 into engagement with the center hole previously formed in the end of the work. The handle 178 is pulled a sufficient distance to put the spring 180 under slight compression and then the handle is depressed so as to engage one of the apertures 188 with the locking pin 190. During the insertion of the work, the spindle 194 is at rest. The operator now depresses the treadle 136. This establishes a driving connection between the main shaft 24 and the spindle and also sets in motion the shaft 252 which carries the cams for advancing the roughening, finishing and pointing tools. During one revolution of the shaft 252 each of the tools comes into play 35 at a predetermined time in the cycle so as to face the underside of the bolt head, form a neck adjacent thereto and also to point the end of the blank. At the completion of this work, the tool carriages are returned and the end 227 of the clutch control lever enters the notch 254 in the timing disc thus breaking the driving connection to the cam shaft 252 and completing the cycle. The operator now lifts the handle 178 to disengage it from the locking pin 190 and by pushing the handle causes the cam slot 170, co-operating with the projecting block 168, to withdraw the dead center 162 and thus permit the bolt blank to be removed.

In Figs. 26 to 28 inclusive, I have illustrated a form of chuck which may be used as an alternative for the one shown at 202 in Fig. 10. This alternative form of chuck includes a body 400 formed with suitable guide slots 402 in which are mounted jaws 404. There are preferably three of these jaws arranged 120° apart as shown in Fig. 26 for engagement with the flats of the hexagonal head of the bolt. The body of the chuck is 55 floatingly secured to the face plate 200 by means of a plurality of shouldered studs 406 which pass through clearance holes 408 formed in the chuck body. Said studs have threaded shanks 410 which are screwed into the face plate 200 and clamping screws 412

serve to lock the studs against accidental turning. The heads 414 of the studs are seated in suitable counterbores 416 as shown.

The jaws 400 are propelled toward and from the center of the chuck by means of adjusting screws 418 whose threads engage the threaded edges 420 of the jaws 404. These adjusting screws are provided with square holes 422 at their ends for coaction with a suitable wrench. At their inner ends, the 70 adjusting screws are notched as at 424 for cooperation with a spring pressed locking pin 426 best shown in Fig. 27. On the face of the chuck a number of index marks 428 are provided opposite the jaws to enable the operator to quickly set the latter for engagement with different sizes of bolt heads.

Because the jaws do not tightly engage the flat portions of the bolt and in view of the clearance between the studs 406 and the holes 408, the chuck can partake of slight relative movement with respect to the face plate 200 to compensate or allow for inaccuracies in the shape of the bolt head. That is to say, if the flats or the apothem of the hexagon is not concentric with the axis of the bolt (which it will be remembered is held on centers) the chuck can move laterally without exerting any substantial strain on the work.

In Fig. 29, I have shown an attachment by which the machine may be turned over by hand. This attachment includes a suitable bracket 430 which may be secured to any fixed part of the framework of the machine in juxtaposition to one of the gears such as at 276 and 268. The bracket 430 carries a boss 432 in which is journaled a stub shaft 434 having a pinion 436 on one end thereof which is adapted to mesh with one of the gears, for example either 276 or 268 according to the location at which the bracket is secured. The end of the shaft 434 opposite the gear 436 is squared off as shown at 438 for engagement with either a wrench or suitable handle by which the operator can rotate the shaft slowly so as to "turn over" the machine for the purpose determining that the various holes have been properly set. The provision of this hand turning attachment saves damaging the parts of the machine due to the operator carelessly securing the cutting tools in their holders in such manner that the cams throw them too great a distance.

The machine shown is well adapted for use in connection with vertical bolt turning and threading machines employing a traveling cutter-head covered by other Eden patents. When used in connection with such turning or threading machines, the output thereof is not held down by the time required for facing the undersides of the heads of blanks and pointing the ends thereof. The bolt blanks are machined in batches with the machine herein described by unskilled operators and the threading and turning of the long shanks 125 130

can be economically done in gang machines of the Eden type having vertically traveling cutter-heads.

Though I have described with great particularity the specific embodiment of the invention illustrated, it is not to be construed that I am limited thereto as various modifications may be made by those skilled in the art without departing from the invention as defined in the appended claims.

What I claim is:

1. In a machine of the class described means for holding the work, a pair of aligned center drills carried in holders having rack teeth, 15 pinions engaging the latter, a sprocket for actuating each pinion, a chain engaging both sprockets and having a weight on one end and the other end being secured to one of said sprockets and a manually operated crank connected with one of said sprockets.
2. In a machine of the class described a separate work holder for holding each end of the work, each holder comprising a pair of coacting jaws, a pair of aligned centering drills, means for simultaneously moving the latter toward the opposite ends of the work including a single manually operated crank, one of said drills and one of said work holders being mounted on a support which is movable to accommodate different lengths of work, an operating member common to both work holders and a weight tending to turn said operating member.
3. In a machine of the class described a work holder comprising a pair of coacting clamp jaws, an actuating cam common to both jaws, a weight arranged to turn said cam and thus exert a gripping action on the work and means for simultaneously drilling centering holes in the opposite ends of the work and a spring tending to release one of said jaws.
4. In a machine of the class described means for holding the work, centering drills, means for advancing said drills toward the ends of the work, means for rotating the work, a plurality of cutting tools and cams for automatically

moving the latter into engagement with the work and driving mechanism for said cams which is rendered non-operative after the work has been rotated a predetermined 50 number of revolutions.

5. In a machine of the class described means for holding the work, centering drills, means for advancing said drills toward the ends of the work, means for rotating the work, facing tools, a shaft carrying cams which advance the tools toward the work and means for automatically interrupting the rotation of said shaft upon the completion of a determined number of revolutions of the work.

6. In a machine of the class described a head stock including a live center and means for rotating the work, a movable tail-stock carrying a dead center and means for drilling centering holes in the work including a fixed 65 work holder adjacent the live center and a holder mounted on the tailstock adjacent the dead center and means for simultaneously actuating both holders.

7. A machine of the class described including a centering drill and a work holder mounted on fixed supports, a similar drill and work holder mounted on a movable support, and respective means for simultaneously actuating both drills and both work holders regardless of the relative position of said movable and fixed supports.

8. In a machine for centering and truing bolt blanks, a pair of work holding members one of which is movable to accommodate 80 blanks of different lengths, centering drills, means for moving the latter toward the ends of the work, means for quickly releasing the holding members, means for rotating the work between centers, a tool for facing the underside of the bolt head, a tool for pointing the end of the blank and means for automatically moving said tools into and out of engagement with the work.

In witness whereof, I have hereunto signed 90 my name.

JAMES A. EDEN, JR.
